SPRAY HEAD

Clifford A. Schacht, Huntington, Ind.

Application February 23, 1933. Serial No. 658,183

3 Claims. (Cl. 4—256)

This invention is a novel improvement in spray heads, and the present application is a continuation-in-part of my copending application for U. S. Letters Patent filed June 4, 1932, Serial No. 5 615,439.

The principal object of the invention is to provide a metallic spray head with a resilient bumper ring stretched around the lower part of the head to prevent the metal head from contacting directly with enameled sinks, bath tubs, or the like, and to protect breakable glassware, dishes, and the like, from injury when using the spray head in the sink; said bumper ring being so designed as to project sufficiently beyond the outer spray-10 ing face of the head so that in event the sink drain should become obstructed with grease or sediment the spray head can be placed over the drain, and the ring will form a tight connection between the spray head and drain, so that water may be forced under pressure into the drain to dislodge any obstruction; also, as the bumper ring protrudes beyond the face of the metallic spray-15 ing face of the head the face will be prevented from contacting with and scratching the sink or other surface.

When water is forced into the drain pipe to dislodge sediment and grease, as the rubber protrudes beyond the face of the spray head a vacuum will be set up between the head and drain 30 whereby it will be easy to hold the spray in place even though the full pressure of the water main is used.

I will explain the invention with reference to the accompanying drawing which illustrates several practical embodiments thereof to enable others to adopt and use the same; and will summarize in the claims the novel features of construction, and novel combinations of parts, for which protection is desired.

40 In said drawing:

Fig. 1 is an elevation of a spray head showing one form of resilient ring mounted upon the outer end of the head, the ring being shown in cross-section.

45 Fig. 2 is a view of the spray head provided with a modified form of ring and showing the spray head being applied to a sink drain.

Fig. 3 is a view showing a further modified form of ring.

50 Fig. 4 is a view showing a further modified form of ring applied to a somewhat different form of spray head.

The metallic spray head A is of conventional form, having its inner end contracted to form 55 a nipple A' for connection with a rubber hose B

leading from the faucet (not shown). The outer end of head A is materially widened and is provided with the usual perforated spray plate A² for diffusing the water issuing from the head. Adjacent the outer or lower end is an external annular 60 rib A³ extending around the spray head, and immediately above the rib A³ the head is provided with an annular recess A⁴ having a substantially semi-circular cross-section.

My novel bumper, as shown in Fig. 1, comprises 65 a rubber ring 1 of substantially circular cross-section, adapted to be stretched around the head and to seat in the annular recessed portion A⁴ of the head. The diameter of ring 1 is preferably greater than the width of portion A⁴, and in the 70 side of ring 1 is molded or otherwise formed a shallow annular recess 1a forming a shoulder for receiving the annular rib A³ of the spray head, whereby ring 1 will be locked securely on the head to prevent same from rolling off, the main 75 portion of the ring being seated in the recess A⁴ of the head. The outer portion of the ring 1 projects slightly beyond the annular rib A³ as indicated in Fig. 1, but does not project beyond the spraying face A². Ring 1 will be molded somewhat 80 smaller in diameter than that of the recess portion A⁴ and rib A³, so that the ring must be stretched in mounting same on the head; the resiliency of the rubber and the engagement of the rib A³ in the recess 1a securely locking the 85 ring in place. The ring 1 acts as a bumper or protector to prevent the metal parts of the spray head from contacting with glassware, dishes, enamel sinks, bath tubs, and the like.

In Fig. 2 a modification is shown in which 90 the rubber ring 10, of somewhat larger circular cross-section than the ring in Fig. 1, is provided with a recess 10a which receives the rib A³, and the recess 10a is made considerably deeper than that in ring 1 of Fig. 1, so that when the ring 95 10 is applied to the head the ring will project beyond the spraying face A² of the head to contact with the sink S (as shown in Fig. 2). As the ring 10 protrudes below the plate A², the latter cannot contact with the sink or the like. Also 100 as the rubber projects below the face of the spray head when the hose B is attached to the faucet, the spray head may be held down over the drain D of the sink S to permit water to be forced down into the drain pipe to free same from sediment, grease and the like. The rubber of the ring 10 forms a tight seal between the head A and sink S to create a suction so that it is very easy to hold the spray in place even though the full pressure of the water in the main be used.

In Fig. 3 a ring 20 of small circular cross-section is used having a relatively deep annular recess 20a in its inner periphery for receiving the annular rib A³ of the spray head; and in Fig. 4 a somewhat similar ring 30 is shown in which the annular recess 30a is shallow to fit the rib A³ of a spray head of slightly different shape. In both Figs. 3 and 4 the rings 20 and 30 do not seat in a recess A⁴, but project below the spray face A² so that the heads may be used to forcibly clean the drain pipe of the sink in the same manner as above described with respect to the head in Fig. 2.

I claim:—

1. In combination with a spray head having an open face and having an outwardly extending annular rib adjacent the open face, a resilient bumper ring of substantially circular cross-section stretched around the head making a tight contact with the rib; the ring having an annular recess in its inner periphery for engagement with the rib for locking the same thereon.

2. In combination with a spray head having a spraying face and having an annular exterior rib adjacent the spraying face, and having an annular recessed portion adjacent the rib; a resilient bumper ring of substantially circular cross-section stretched around the recessed portion, said ring having an annular recess in its face receiving the rib for locking the ring on the head.

3. In combination with a spray head having a spraying face and having an annular exterior rib adjacent the spraying face, and having an annular recessed portion adjacent the rib; a resilient bumper ring of substantially circular cross-section stretched around the recessed portion, said ring having an annular recess in its face receiving the rib; and the ring protruding beyond the spraying face of the head for effecting a tight seal beyond the spraying face, when contacting with a surface.
